United States Patent

Des. 239,845

Patented May 11, 1976

239,845

SLIDE-IN, SLIDE-OUT PLAY POOL

Ascher Chase, Norfolk, Va., assignor to General Foam
Plastics Corp., Norfolk, Va.

Filed May 17, 1972, Ser. No. 254,353

Term of patent 14 years

Int. Cl. D21—03

U.S. Cl. D34—5 F

Fig. 1

Fig. 2

Fig. 3

Fig. 4

FIG. 1 is a front perspective view of a pool embodying my new design;

FIG. 2 is a rear perspective view of the pool of FIG. 1; and

FIGS. 3 and 4 are side perspective views of the pool of FIGS. 1 and 2.

I claim:

The ornamental design for a slide-in, slide-out play pool, substantially as shown.
